CHANGE-OVER DEVICE

James J. Shanley, Bartlesville, Okla., assignor to
 Phillips Petroleum Company, a corporation of
 Delaware

Application February 19, 1940, Serial No. 319,787

4 Claims. (Cl. 62—1)

The present invention relates to improvements in devices for automatically changing withdrawal connections from one source of high pressure gas to another upon decrease in pressure in the first source.

Liquefied petroleum gas, such as propane, butane, or a mixture of the two, is now being marketed extensively in tanks or cylinders. In making use of this liquefied gas for operating gas consuming appliances, such as domestic gas ranges, it is customary to provide the customer with two containers with some means of connecting them to a service line through a suitable arrangement of valves and pressure regulators. The usual procedure is to use one of the cylinders as the active source of the gas supply, keeping the other cylinder as a reserve source until the first cylinder is exhausted. It is then necessary to cut off the exhausted source and establish connection with the reserve source. In prior practice, the valve on the active cylinder was opened while the valve on the reserve cylinder was kept closed. When the gas in the active cylinder became exhausted the valve on that cylinder was closed and the valve on the reserve cylinder opened. The disadvantage of this system was that the customer had to go to the place where the cylinders were housed, usually outside, and change the valves each time one of the containers became depleted. Sometimes, a container became depleted at night or while the customer was not at home and the result was that there was a cessation in the gas supply and all pilot lights were extinguished. Recently there have been developed various systems equipped with so-called automatic valves, whereby upon the pressure in the active container becoming low, the vapor in the reserve container will be drawn upon but the valve must be reset for a second cycle. For some time it has been desirable to produce a fully automatic changeover device that does not have to be previously set manually before it effects a changeover of withdrawal connections.

An important object of this invention is to provide an improved automatic changeover device that will be entirely automatic in its operation.

An additional object of the present invention is to provide an automatic changeover device of simplified construction and positive operation.

Other objects and advantages of this invention will become apparent from the following detailed description thereof, reference being had to the accompanying drawing which constitutes a part of this specification, and wherein:

Figure 1 is a view in vertical section of a device embodying the present invention.

Figures 2 and 3 are enlarged fragmentary views of some of the elements shown in Figure 1 and illustrating movements of the same.

Referring more specifically to the drawing, reference numeral 8 designates a casing or body member having inlet conduits 9, 10, and an outlet conduit 11. The valve cores or any other suitable valves 12 and 13 close inlet conduits 9 and 10 respectively. Valve stems 14 and 15 of the valves are situated on the casing side of the valves.

A rigid partition 16 divides the casing into two compartments which are joined for gas flow by peripheral passages 17. On each side of rigid partition 16 there are positioned diaphragms 18 and 19 forming sealed diaphragm chambers 20, 21. The inlets adjacent the valves carry check valves 22, 23. The inlets on the upstream side of the check valves are connected by passages 24, 25 with diaphragm chambers 21, 20 respectively. The diaphragms carry pins 26, 27 each having a lateral projection 28 on its extreme end (see Figure 3). A valve stem operating pin 29 slidably carried by a hanger 30 is present in each compartment of the casing 8. Each pin 29 is connected to a compression spring 31 in such a manner that a quick acting switch effect is accomplished by moving the pin past an intermediate or dead center position (see Figure 2). A rotatable cam 32 having camming members 33 and 34 is connected by an arm 35 with a link 36 which in turn is connected to pin 29. Abutment members 37 limit movement of pins 29 away from the valve stems.

Movement of diaphragm pin 27 from the position shown in Figures 1 and 3 upward will result in spring 31 snapping pin 29 into contact with valve stem 14 to open valve 12. The position of the parts at this point are shown in dotted lines in Figures 2 and 3. Movement of diaphragm pin 27 downwardly from the position shown in Figure 3 will cause spring 31 to snap pin 29 out of contact with valve stem 14.

With a full cylinder connected to inlet 9 and with 10 pounds gas pressure present at that inlet, the 10 pounds pressure will be applied through passage 24 to diaphragm 19 and the pressure in casing 8 being atmospheric, the diaphragm 19 and its pin 27 will move upwardly to cause pin 29 to open valve 12. When a cylinder is then connected to inlet 10 which terminates at valve 13, the 10 pounds applied through passage 25 to diaphragm 18 will not appreciably move the

same since the pressure in casing 8 is now approximately 10 pounds minus the small pressure drop across valve 12. When the gas flowing through the valve 12 begins to drop in pressure due to depletion of the liquefied gas in the associated cylinder, the pressure in diaphragm chamber 21 will also begin to drop and the pressure in casing 8 will begin to drop. At the same time due to the fact that the pressure in diaphragm chamber 20 is being maintained at 10 pounds, diaphragm 18 and its pin 26 will begin to move outwardly until at a pressure of, for example, 7 pounds in casing 8, valve 13 will open by the sequence of actions described above for valve 12. The pressure in casing 8 will immediately rise to approximately 10 pounds, check valve 22 will close and diaphragm 19, due to the pressure differential present, will move downwardly operating cam member 32 as will be obvious in Figure 3 to snap pin 29 off valve stem 14.

It will be understood that the valve operating member made up of elements 29, 30, 31, 32, 33, 34, 35, 36, and 37 in the disclosed embodiment may be of any desired construction so long as the valve contacting element is movable between two positions by being moved past a dead center position or its equivalent.

While I have herein described and illustrated a preferred example of my invention, it is to be understood that various changes may be made in size, shape, and arrangement of parts without departing from the spirit of my invention as expressed in the following claims.

I claim:

1. A changeover device comprising two inlet conduits, an outlet conduit connected to the inlet conduits, a valve controlling each inlet conduit and normally urged into closed position, a valve operating member for each valve movable between two positions and opening the associated valve in one of the two positions, fluid pressure operated means associated with the valve operating members to change the position of the same, the fluid pressure operated means being

subjected to the pressure in the outlet conduit, and means for applying an operating pressure to the fluid pressure operated means from a point in each inlet conduit.

5 2. A changeover device comprising two inlet conduits, an outlet conduit connected to the inlet conduits, a valve controlling each inlet conduit and normally urged into closed position, a valve operating member for each valve movable between two positions and opening the associated valve in one of the two positions, fluid pressure operated means associated with each valve operating member, means for applying the pressure differential between the associated inlet conduits and the outlet conduit to the fluid pressure operated means.

10 3. A changeover device comprising a body member having two fluid inlets and a fluid outlet, conduits connecting the inlets and the outlet, 20 valve means including a valve controlling each conduit, valve operating means having two positions associated with each valve and acting to open the associated valve in one position, fluid pressure operated means operable in response to pressure differential across the valve means to move the valve operating means from one position to the other.

25 4. A changeover device comprising two inlet conduits and an outlet conduit, a valve controlling each inlet conduit normally in closed position, a valve operating member for each valve, each valve operating member movable from one extreme position to another and acting to open its associated valve in one position, fluid pressure operated means associated with each valve and acting in response to pressure differential between a point on one side of the valve and the outlet conduit, connecting means acting between the valve operating members and the fluid pressure operated means to move a valve operating member from one extreme position to another on the presence of a predetermined pressure differential on the fluid pressure operated means.

JAMES J. SHANLEY.
